**PORTABLE VACUUM FILTER OR THE LIKE FOR
SWIMMING POOLS**

Earl C. Wallace, Andrews, and James J. Meekin, Huntington, Ind., assignors to The Hettrick Manufacturing Company, Toledo, Ohio, a corporation of Ohio

Application December 3, 1956, Serial No. 44,054

Term of patent 14 years

(Cl. D9—2)

Fig. 1

Fig. 2

Figure 1 is a front perspective view of the portable vacuum filter or the like for swimming pools showing our new design; and

Figure 2 is a rear perspective view thereof.

The portions shown broken away in Figures 1 and 2 are for the purpose of indicating indeterminate length.

We claim:

The ornamental design for a portable vacuum filter or the like for swimming pools, as shown and described.
